UNITED STATES PATENT OFFICE.

GEORGE E. BRETT, OF BIRMINGHAM, ALABAMA.

DESIGN FOR A BOTTLE.

51,409.

Specification for Design. Patented Oct. 23, 1917.

Application filed July 20, 1917. Serial No. 181,909. Term of patent 14 years.

To all whom it may concern:

Be it known that I, GEORGE E. BRETT, a citizen of the United States, residing at Birmingham, in the county of Jefferson and State of Alabama, have invented a new, original, and ornamental Design for Bottles, of which the following is a specification, reference being had to the accompanying drawings, forming a part thereof.

The figure is a side elevation of a bottle of the type customarily used for soft drinks and beer showing my new design.

I claim:—

The ornamental design for a bottle as shown.

GEORGE E. BRETT.
